UNITED STATES PATENT OFFICE

CHRISTIAN SCHNEIDER, OF NEUROESSEN, GERMANY, ASSIGNOR TO I. G. FARBEN-INDUSTRIE AKTIENGESELLSCHAFT, OF FRANKFORT-ON-THE-MAIN, GERMANY, A CORPORATION OF GERMANY

FIRE-EXTINGUISHING PROCESS

No Drawing. Application filed March 7, 1929, Serial No. 345,923, and in Germany March 14, 1928.

The extinguishing of fires of combustibles, such as coal, brown coal, and particularly of finely divided combustibles, such as coal dust, cotton or cotton dust, cork meal and the like, with water is known to be difficult and may lead to explosions when extinguishing a burning dust.

I have found that fires of burning or glowing materials, such as coal, coal dust, paper, wood, straw, cotton, wool and the like, can be easily extinguished by preparing an aqueous solution of a wetting agent and spouting or spraying it onto the burning combustibles. Such wetting agents are, for example, soaps or saponin, but the sulphonation products of organic compounds, namely sulphuric esters or sulphonic acids and particularly their salts, which are equivalents to the said esters or acids for the purposes of the present invention, are most efficient. The said sulphuric esters and sulphonic acids comprise Turkey red oil and similar acid sulphuric esters of fats and oils or fatty acids and the sulphonic acids of aliphatic, cycloaliphatic, partially hydrogenated aromatic and mono- or poly-nuclear aromatic compounds, and especially those of the cyclic compounds which are substituted by alkyl or aralkyl radicals. Also mixtures composed of such sulphonation products or the mixtures obtainable by sulphonating mineral oils or tars or fractions thereof can be favorably employed. These materials can be employed as such or in the form of their salts and can be either added to the water, or the readily inflammable substances can be sprayed therewith so that, in the case of ignition, the burning substances are thoroughly and quickly penetrated by the water sprayed thereon and thereby wetted.

When a highly movable burning combustible, such as fine brown-coal dust is to be extinguished, the solutions according to the present invention are preferably sprayed by means of a nozzle onto the burning material in order to avoid flame jets.

The amount of the material to be employed which is capable of reducing the surface tension of water can be varied within wide limits, even a very small percentage by

weight of the water employed, or of the combustibles, being most efficient.

It was to be expected that on spraying solutions of the aforesaid wetting agents a combustion thereof would occur prior to the wetting action, but this is not the case. The solutions prepared and applied according to the present invention exhibit the particular advantage over the hitherto known foam producing fire extinguishing agents which contain protective colloids, such as glue or aluminium hydroxide, that there is formed practically no foam on the combustibles, which agents in many cases would render the combustibles useless for their original destination.

The following examples will further illustrate the nature of the said invention, but the invention is not limited to these examples.

Example 1

From 1 to 2 parts of the sodium salt of a naphthalene sulphonic acid containing one or more propyl or butyl groups in its molecule are added to each 100 parts of water. On extinguishing fires, such as burning brown coal, by spraying the said mixture onto the burning material, the mixture penetrates the burning material much more quickly than pure water, so that a striking result as regards extinction is produced. Instead of the aforementioned salts, grain soap, Turkey red oil or similar compounds can be employed, but the aforesaid salts are more efficient.

Example 2

Burning linseed is easily extinguished by adding to the water intended for extinguishing, about 1 per cent its weight of a butylated naphthalene sulphonic acid, and spraying or spouting the solution onto the burning material.

Example 3

Burning brown coal dust deposited in a closed room is easily extinguished by introducing wet steam into the same after the steam has been loaded with a highly efficient wetting agent, such as sulphonated min-

eral oil or tar oil or naphthenic acid or tall oil sulphonation products, butylated, amyloated or benzylated napthalene sulphonic acids or naphthalene sulphonic acids containing several of the aforesaid substituents, for example benzyl iso-propyl napthalene sulphonic acid and chlorinated sulphonic acids of the aforesaid series, for example, by passing a solution thereof or by spraying steam and the solution through a mixing nozzle.

0 What I claim is:

1. A process for extinguishing fire which comprises bringing a dilute aqueous solution of a highly effective wetting agent containing an acid group into contact with the burning material.

5 2. A process for extinguishing fire which comprises bringing a dilute aqueous solution of a strongly wetting sulphonation product of an organic compound into contact with the burning material.

20 3. A process for extinguishing fire which comprises bringing a dilute aqueous solution of a strongly wetting sulphonation product of a mixture of organic compounds into contact with the burning material.

25 4. A process for extinguishing fire which comprises bringing a dilute aqueous solution of a sulphonic acid of an aromatic compound into contact with the burning material.

30 5. A process for extinguishing fire which comprises bringing a dilute aqueous solution of a sulphonic acid of a polynuclear aromatic compound into contact with the burning material.

35 6. A process for extinguishing fire which comprises bringing a dilute aqueous solution of a sulphonic acid of an aromatic compound containing an alkyl radicle in its molecule into contact with the burning material.

40 In testimony whereof I have hereunto set my hand.

45 CHRISTIAN SCHNEIDER.
